UNITED STATES PATENT OFFICE

ANNIBALE A. GUERINI, OF NEW YORK, N. Y.

WALL-PLASTERING MACHINE

Application filed April 4, 1927. Serial No. 180,680.

My invention consists in a machine which may be employed for plastering walls, ceilings or for applying cement to floors.

The object of the invention consists in a machine which will readily and uniformly apply the desired plastering material upon any surface, and therefore serve to radically decrease the cost of plastering operations.

For the purpose of illustration, I have chosen to show in the accompanying drawings apparatus intended for use in plastering walls, but it will be apparent that this apparatus is capable of modification for plastering ceilings or for applying cement to floors without departing from this invention.

Speaking generally, the apparatus of this invention embodies a plastering board which is adapted to be moved either manually or mechanically in parallel relation to and in juxtaposition with the surface to which the mortar or plaster is to be applied and this board is mounted upon a suitable frame, whereby it is manipulated, which serves as a carrier therefor in such manner that the board will be in inclined relation to the surface to which the plaster is to be applied. The plaster is adapted to be deposited upon the board which because of its inclination cooperates with the wall surface to form a hopper to hold the plaster, and means is provided for stirring or agitating the plaster to cause it to be fed and applied to the surface. Means is also included in the apparatus for laterally shifting the plaster board concurrently with the travel of the board over the surface to be plastered. This latter movement is not essential for all plastering work, but is particularly desirable in the application of rough or first coats which generally embody some sort of binding fibre.

I wish to particularly call attention to the employment in the present apparatus of the plaster board with associated stirring means. I consider this arrangement highly desirable because through the use of the stirring means, the inertia of the plaster is overcome and it is moved more readily to the surface to be plastered and is more efficiently applied to such surface when agitated during application. The employment of means for trans-

versely reciprocating the plaster board during the application of the plaster is, as stated, highly desirable in applying first coats to lath or other backing, but while this feature is highly efficient such lateral movement is not essential in the application of finished coats and the present invention is further not limited to an apparatus embodying such means.

In the preferred form of the present invention, the plaster board is mounted in inclined position upon a suitable frame, and agitators which are associated therewith are operated by a common prime mover which at the same time serves to cause travel of the board over the surface to be plastered. If lateral movement of the board is also desired mechanism for accomplishing this result may be also driven from the prime mover which, in practice, may conveniently be an electric motor.

I am aware that the invention may partake of different practical forms, without departing from the inventive concept.

Features of the invention, other than those specified, will be apparent from the herein-after detailed description and claims, when read in conjunction with the accompanying drawings.

The accompanying drawings illustrate one practical embodiment of the invention, but the construction therein shown is to be understood as illustrative, only, and not as defining the limits of the invention.

Figure 1 is a side elevation of a machine. Figure 2 is a section on the line 2--2 of Figure 3.

Figure 3 is an elevation looking from the back of the machine or from the side thereof away from the wall.

Figure 4 is a longitudinal section taken on the line 4--4 of Figure 1.

Figure 5 is a perspective view showing the machine of this invention, certain parts being broken away in the interest of clearness.

The supporting frame of the machine embodies members 1, 2, 3, 4, 5, 6, 7, 8, 9, 10 and 11. On the frame is mounted a motor 12 which drives a worm 13. This worm 13 meshes with a worm wheel 14 mounted on a

shaft 15. This shaft has two cranks 16 and 17, and also carries a drum 18. Also fixed on the shaft are two gears 19 and 20, the former gear is conventional, while the latter gear is a mutilated gear. That is to say, the gear 20 is provided with teeth only for one-half of its periphery, the other half being smooth and without teeth. Mounted in the frame in parallel relation to the shaft 15 and spaced laterally therefrom a short distance is a counter shaft 23 on which is mounted two gears 22 and 24, the former of which meshes with the gear 19, and the latter of which is positioned to the side of, but does not mesh with the gear 20. The gear 24 is mutilated in the same manner as the gear 20, but it is set oppositely to the gear 20. These two mutilated gears 20 and 24 are adapted to co-operate with a rack 25 in such manner that when the gear 20 is in mesh with the rack, the gear 24 will be out of mesh therewith and vice versa. In other words, these gears alternately mesh with the rack.

The rack 25 is mounted on screws 26 and 27 threaded through cushions 28 which are supported on the frame 29, which, in turn, supports the plastering board and the alternate working of the intermittent gears will cause lateral reciprocation of the plastering board when these gears are operated. When lateral motion is not desired or needed, the rack 25 is disengaged from the gears 20 and 24 by backing down the screws 26 and 27.

The portion 8 of the frame is rectangular in form and mounted thereon are antifriction wheels 30 which are positioned at each end of the frame. In addition to the wheels 30, there are other antifriction wheels 31 and 32 at the top and bottom members of this frame, so as to provide for the movement of the frame 29 with respect to the frame 8 with minimum friction.

Secured to the opposite ends of the frame 8 and upstanding therefrom are arms 33, two of which are at each end of the frame and these arms are provided with a plurality of holes through which screws may be passed to secure catches 34 in position on said frame. The holes in the arms 33 are made so that the screws may be shifted from one set of holes to another in order to mount the catches in the desired adjustment to determine the thickness of the mortar which is to be applied to the wall. Supported on the upstanding forward edge of each catch is a shoe 35 adapted to ride against the wall and guide the plaster board during its operations as hereinafter more fully explained.

Each of the shoes is pivoted at its lower end on a pivot 36 and is provided near its upper end with a screw 37 by which proper adjustment may be had.

The two catches 34 are spaced apart and rendered relatively rigid by means of bars 38, 39, 40 and 41, which are transversely slotted

or grooved, as shown in Figure 4, to receive ribs at the upper edges of partitioning fins 42 which are thus supported on the bars 38-41 and divide the chamber between the catches into smaller chambers. These fins are readily detachable and are inserted only when the machine is to be operated to apply mortar by running the machine vertically, although they may be used whenever it is desired to localize the plaster, for example, in proximity to doors, windows, etc.

The plaster board embodies a rectangular frame 29 to which is secured the plastering board proper 43. Hooks 44 and 45 are secured to the top and bottom of the frame 29 and engage with the antifriction rollers 31 and 32 to properly support the frame 29 on the frame 8. The lateral members of the frame 29 are provided with rectangular openings 46 (see Figures 3 and 4).

The plastering board 43 rests on the antifriction wheels 30 with the hooks 44 and 45 hooked over the antifriction wheels 31 and 32 and the arms 33 passing through the openings 45. The length of these openings will be sufficient to permit of the lateral movement of the plastering board when desired.

The plastering board 43 is provided at its opposite ends with upturned lips 47 which cooperate with the catches to form the opposite sides of the plastering board. The openings 45 are closed by the plates 48 which are secured to the arms 33.

Between the two uprights 50 of the frame of the apparatus extends a shaft 51, see Figures 1, 2 and 3, and on this shaft are pivotally mounted bell cranks 52-55 and 53-54. The bell cranks 52-55 are coupled together by a rod 56 and the bell cranks 53 and 54 are coupled together by a rod 57. The rods 56 and 57 are respectively secured by connecting rods 58 and 59 to the cranks 16 and 17 of the shaft 15. To the other arms of the bell cranks 53 and 54 is secured a bar 60 on which are attached tampers 61, while the bar 62 is secured to the bell cranks 52-55. Tampers 63 are carried by this latter arm.

The apparatus as thus far described is all mounted on and supported by the frame which embodies the members 1 to 11. The apparatus may be operated by hand and is provided with handles 49 secured to the frame elements 7 for this purpose. An additional handle 81 is also provided for manipulating the apparatus at heights where the operator can not reach by grasping the handles 49. Provision is made, however, for the manipulation of the apparatus by power. To this end a lifting frame is provided. This lifting frame is composed of two upright channelled members 64 and 65 which are vertically adjustable to vary their height. The top parts of these uprights are united to the lower parts by worms 66 which turn in smooth holes in blocks 67 secured to the lower sec-

tions of the uprights and work in threaded holes in blocks 68 carried by the upper sections. The channels 64^a and 65^a are extended to overlap the joints between the two sections for the length equal to the length of the worms 66, so that the channels in these uprights are substantially continuous irrespective of the adjustments made. At the top of each upright is a laterally extending arm 69 to which arms are secured sleeves 70 and through the sleeves 70 a bar 71 is passed. By this arrangement, the uprights may be positioned at different distances apart and the bar 71 manipulated to provide for this adjustment. When the parts are in adjusted position, thumb screws associated with the sleeves 70 serve to secure the parts in adjustment.

The bar 71 forms a support for a pulley 72 and over this pulley extends a cable 73. One end of the cable is wrapped around the drum 18 and the opposite end is secured by a rig or bale to a horizontal beam 74. This beam together with the beam 76 passes through sleeves secured to the vertical uprights 50 and the length of these beams may be increased or decreased by sliding the beams longitudinally with respect to short beam sections 78 associated with the opposite ends of the longer beams. The ends of each of the short beams are provided with antifriction rollers 79 which extend into the channels of the uprights and springs 80 serve to maintain the rollers 79, in a manner to take up lost motion.

The preferred form of apparatus of this invention which has been set forth in the foregoing detailed description operates in the following manner.

The mortar used for plastering the walls is composed of different ingredients and in the first coat, such as is generally applied to lath, it embodies some kind of fibre. In this case, it will be found desirable to manipulate the plaster board in such manner that it will partake of lateral reciprocation while traversing the wall vertically. Assume, therefore, that the machine is started with the rack 25 in engagement with the mutilated gears 20 and 24. As the machine is started with the apparatus in its lowermost position adjacent the floor of the room, mortar is deposited upon the plaster board and as the mortar is introduced the machine should commence to operate. The motor 12 is energized by pressing the switch button 82 and the worm 13 immediately commences to rotate. The worm serves to drive the shaft 15, which causes reciprocation of the tampers simultaneously causing the plaster board to reciprocate through the gears 20 and 24 and the rack 25 and at the same time, the apparatus is raised by the winding of the cable 73 upon the drum 18.

As the apparatus moves upwardly along the wall, the tampers thoroughly agitate the

mortar upon the plastering board and in thus overcoming its inertia or its tendency to stick to the board, assists gravity in feeding the mortar to the wall, where it is deposited in a layer of desired thickness depending upon the adjustment of the catches and shoes as will be apparent. The lifting operation of the board will be accompanied by a lateral vibratory or reciprocating movement which will efficiently distribute the mortar upon the wall surface. If the apparatus is to be manipulated manually and without employing a supporting frame, the cable 73 and said frame are removed from the assembly and the operator after starting the machine grasps the handles 49 and slowly raises the apparatus until it has reached a height where further manipulation while holding the handles would be inconvenient. The operator then grasps the handle or board 81 and continues to raise the apparatus until it reaches the ceiling.

The operation as thus far described contemplates simultaneous raising movement and lateral reciprocation, but at times lateral reciprocation is not necessary and in such cases, the rack 25 may be lowered out of engagement with the gears 20 and 24 to thus disconnect the lateral shifting mechanism. The speed at which the apparatus operates will of course depend upon particular conditions, namely, the consistency of the mortar or plaster to be applied, the constituents entering into such mortar or plaster, and other features which will be apparent to those skilled in the art. Anyone familiar with plastering may, however, readily determine the speed of operation of the machine to obtain the best results. The motor 12 is preferably a variable speed motor in order to permit of very flexible adjustment in speeds.

I wish to call particular attention to the advantages obtainable by the use of the tampers as described. They not only assist gravity in feeding the plaster to the wall, but also effect a more or less positive feed of plaster to cause it to firmly impinge the wall surface. This agitation of the plaster or mortar is highly desirable and while tampers are shown for this particular purpose, other equivalent stirring devices may be employed in lieu thereof. The utilization of an inclined board is a further important feature of this invention either as considered with or without the lateral reciprocation or vibration caused when using an inclined board, the mortar is very efficiently fed to and distributed over the wall surface without any tendency of the board to drag on the plaster and produce a roughened surface.

When the board is tilted or inclined as described, its operation closely simulates a troweling action which, in practice, is found to give the best results.

The foregoing detailed description sets

forth the invention in its preferred practical form, but inasmuch as the invention may be varied in details without departing from the spirit thereof, it is to be understood as fully commensurate with the appended claims.

This application forms, in part, a continuing case of my allowed application, Serial No. 718,961, filed June 9, 1924.

Having thus fully described the invention, what I claim as new and desire to secure by Letters Patent is:

1. In a plastering machine, the combination of a plastering board, an inclined frame on which the plastering board is mounted for edgewise movement, means for moving the frame and plastering board along the surface to be covered, means for moving the plastering board relative to the frame and transversely across the surface to be covered, together with means progressively feeding the plaster along the plastering board, towards the surface to be covered.

2. In a plastering machine, the combination of a movable frame, a plastering board supported by said frame for edgewise rectilinear movement, means for moving the plastering board on the frame along the surface to be covered, means for moving the plastering board on the frame transversely of the surface to be covered, and means on the frame for feeding the plaster along the plastering board, toward the surface to be covered.

3. In a plastering machine, the combination of a frame, an angularly disposed plastering board mounted for edgewise movement on the frame, means for moving both the frame and plastering board edgewise with respect to the frame and along the surface to be covered, means for moving the plastering board across the surface to be covered, and means for progressively feeding the plastering material towards the surface to be covered.

4. In a plastering machine having the characteristics of claim 1, the addition of means for altering the inclination of the plastering board when desired.

5. In a plastering machine having the characteristics of claim 1, the addition of anti-friction means for supporting the plastering board in its transverse movement.

6. In a plastering machine, the combination of a movable frame, a plastering board supported by said frame and adapted to receive and carry plastering material, means for moving the plastering board on the frame along the surface to be covered, means for moving the plastering board on the frame transversely of the surface to be covered, and means on the frame for stirring and tamping the plaster and to feed said plaster along the plastering board, towards the surface to be covered.

7. In a plastering machine, the combina-

tion of a frame, an angularly disposed plastering board and adapted to receive and carry plastering material, means for moving said plastering board along the surface to be covered, means for moving the plastering board across the surface to be covered, and means for stirring and tamping the plastering material to feed it towards the surface to be covered.

8. In a plastering machine, the combination of a frame, worms carried by the said frame, means for giving motion to the worms, movable means carried by the worms, a plastering board carried by the movable member and adapted to receive and carry plastering material, together with means for giving transverse movement to the plastering board as it moves over the surface to be plastered, and means for stirring and tamping plaster upon the plastering board to feed the plaster toward the surface to be covered.

9. In a plastering machine, the combination of a suitable frame, an angularly disposed plastering board supported on the frame and on which board mortar is adapted to be deposited, means associated with the board for stirring the mortar thereon, and means for moving the plastering board along the surface to be covered.

10. In a plastering machine, the combination of a suitable frame, an angularly disposed plastering board carried by the frame and on which board mortar is adapted to be deposited, and guiding means adapted to bear against the surface to which the mortar is to be applied to space the plastering board uniformly from the said surface as the board is moved thereover.

11. In a plastering machine, the combination of a plastering board adapted to receive and carry plastering material, means for moving said board along the surface to be covered and relative to the frame, together with means for stirring the mortar along the plastering board toward the surface to be covered.

12. In a plastering machine, the combination of a plastering board adapted to receive and carry plastering material, means for moving the plastering board along and across the surface to be covered and relative to the frame, together with means for stirring the mortar along the plastering board toward the surface to be covered.

13. In a plastering machine, the combination of a frame, a plastering board adapted to receive and carry plastering material, means for moving the plastering board along and across the surface to be covered and relative to the frame, and means on the frame for stirring the mortar along the plastering board toward the surface to be covered.

14. In a plastering machine, the combination of a frame, an angularly disposed plastering board adapted to receive and

carry plastering material, means for moving the plastering board along and across the surface to be covered and relative to the frame, and means for stirring material toward the surface to be covered.

5 15. In a plastering machine, the combination of a frame with means to support the frame in inclined position with respect to the wall to be plastered, a plastering board mounted for lateral edgewise movement on the frame, and rack and pinion connections between the frame and the plastering board, and means for operating the rack and pinion connections to reciprocate the plastering board laterally as the frame and plastering board are held in proximity to the wall to be plastered.

10 16. In a plastering machine, the combination of a suitable supporting frame, a plastering board mounted on the frame for edgewise reciprocation thereon, and means carried by the frame and plastering board for imparting edgewise reciprocation to the board with respect to the frame, and means for stirring and tamping plaster deposited upon the plaster board for the purpose of moving such plaster in a direction of one edge to the plastering board adapted to be supported in cooperative relation to the wall to be plastered.

15 17. In a plastering machine, a plastering board, means for supporting the plastering board in inclined position in spaced relation to the wall to be plastered, and tamping devices reciprocating along a surface of the board toward and away from the wall to be covered for moving the plaster down the inclined board to the wall.

20 18. In a plastering machine, a plastering board adapted to be moved in inclined position along the surface to be plastered, and on which board mortar is adapted to be deposited, guides bearing against the surface to be plastered to space the lower edge of the board from said surface, and means associated with the board for stirring and tamping the mortar down the inclined surface of the board toward the wall surface.

25 19. In a plastering machine, a suitable frame, means for supporting said frame and guiding same for up and down movement, a plastering board supported in inclined position on the frame for edgewise lateral reciprocation and adapted to receive and carry plastering material, guiding means mounted on the frame for guiding the frame in its up and down movement and for spacing the lower edge of the plastering board a predetermined distance from the surface to be plastered, means mounted on the frame for laterally reciprocating the plastering board, and tampers operable adjacent the surface of the board to move the girder thereon toward the lower edge of the board.

30 20. In a plastering machine, a suitable

frame, means for supporting said frame and guiding same for up and down movement, a plastering board supported in inclined position on the frame for edgewise lateral reciprocation and adapted to receive and carry plastering material, guiding means mounted on the frame for guiding the frame in its up and down movement and for spacing the lower edge of the plastering board a predetermined distance from the surface to be plastered, and means mounted on the frame for laterally reciprocating the plastering board, and tamping rods operating adjacent the face of the board in a direction substantially parallel to the face of the board and toward and away from the lower edge of said board, and means on the frame for operating the tampers to force plaster deposited on the board in the direction of the surface to be plastered.

In testimony whereof I have signed the foregoing specification.
